UNITED STATES PATENT OFFICE.

DENIS HENRY O'MEARA, OF DETROIT, MICHIGAN, ASSIGNOR TO AMERICAN OPTICAL COMPANY, OF SOUTHBRIDGE, MASSACHUSETTS, A VOLUNTARY ASSOCIATION OF MASSACHUSETTS.

MAGNIFIER.

Application filed April 14, 1924. Serial No. 706,428.

To all whom it may concern:

Be it known that I, DENIS HENRY O'MEARA, a citizen of the United States, residing at Detroit, in the county of Wayne, and State of Michigan, have invented certain new and useful Improvements in Magnifiers, of which the following is a specification.

The present invention relates to an improved magnifier and has particular reference to a device wherein the lens may be raised and lowered with respect to the objects viewed therethrough, the lens also being adapted for angular adjustment.

15 A very important object of this invention is to provide a magnifier that may be collapsed when not in use, and which may be swung into an operative position easily and quickly when desired.

20 Another important object of the invention is to provide a collapsible magnifier wherein the lens is carried by an adjustable supporting member whereby the lens may be moved to and from the objects viewed 25 through the lens while at the same time the angle of the lens with respect thereto may be adjusted to suit the needs of the user.

Another important object of the invention is to provide a magnifier which is particularly well adapted for use as a reading 30 glass, the said magnifier being of such a nature that it may be collapsed and carried about without any difficulty.

Other objects and advantages of the invention will become apparent during the 35 course of the following description.

In the drawings, wherein like numerals are employed to designate like parts throughout the same:

40 Figure 1 is a perspective view of one form of my improved magnifier illustrating the lens raised into an operative position;

Figure 2 is a sectional view of a slightly modified form indicating several of the positions in which the lens may be swung;

45 Figure 3 is a fragmentary detail of another form of the invention;

Figure 4 is a top plan of another form of the invention;

50 Figure 5 is a side elevation thereof;

Figure 6 is a view of a case in which the magnifier may be carried when not in use.

In the drawings, wherein for the purposes of illustration is shown the preferred em-

bodiment of the invention, the numeral 10 55 designates, in Figure 1, one form of base which is used in connection with my magnifier. In this instance the base 10 is in the form of an annular band which, however, may be circular or of other cross sectional 60 configuration. In Figure 1 the base 10 is provided with the diametrically opposed ears 11, to which are pivotally or hingedly connected the lens supporting brackets 12. The brackets 12 are connected to the ears 65 11 by means of suitable bolts, pins, or the like, 13.

The opposite ends of the brackets 12 terminate in the annular extensions 14, which extend in substantially parallel relationship 70 to each other. The lens proper of the magnifier is designated by the numeral 15 and is retained within a suitable rim, or the like, 16, which is provided with the outwardly extending projections 17 which are adapted 75 to be hingedly arranged between the angular extensions 14 of the bracket members 12. A pin or the like 18 is provided to permit of a pivotal movement of the lens 15 and frame 16. The frame 16 is preferably of 80 the split kind so that the lens 15 may be removed or replaced as desired, while the ends of the rim 16 provide the necessary extensions 17 by which means the lens and frame are hingedly or pivotally connected to the 85 lens supporting brackets 12.

It is to be noted that due to the arrangement of the lens supporting brackets 12, angular extensions 14 and projections 17, the magnifier may be collapsed when not 90 in use. This will permit of easy carrying of the magnifier, where the magnifier is designed and used for reading purposes. However, the magnifier is not restricted to use as a reading glass, as it may equally 95 well be used wherever magnifiers have heretofore been used.

In Figure 2 of the drawings a slight modification is shown wherein the supporting bracket 19 is hingedly connected or 100 mounted upon the base 20 as at 21. In this instance no additional ears are provided, the bracket 19 being pivoted directly through the frame 20. In this instance the lens 22, which is carried by the frame 23, is likewise pivoted as at 24 to the lens supporting bracket 19. As is shown in dotted lines in Figure 2, the lens 22 and frame 23 may

be adjusted angularly as respects the base 20, while at the same time the supporting bracket 19 may be swung in either direction so as to adjust the relative height of the 5 lens with respect to the base. In this way it is to be noted the lens 22 may be focused upon the object seen therethrough in accordance with the specific requirements of the user as well as the angle of the lens with 10 respect to the base, depending upon the position of the user.

In Figure 3 the base 25 is preferably of a semicircular configuration, while the lens supporting brackets 26 are pivotally connected thereto as at 27. It is to be understood that the shape of the base 25 is not necessarily semi-circular. In this instance to provide means for rigidly supporting the lens in adjustment, a handle 28 is carried by 20 the base 25 which acts as a brace as well as a handle. By having the base substantially of the configuration as shown, the lens may be moved relatively close to the object viewed without the base interfering, as at 25 least half of the portion under the lens is devoid of the base member.

In Figures 4 and 5 is shown a slight modification of the magnifier shown in Figure 1, in that the lens 29 is angular instead 30 of round. This is likewise carried by the lens supporting brackets 30, which brackets are supported by the base 31. The magnifier may be collapsed and placed within the case 32 and thus carried around conveniently, while at the same time it may be removed from the case and set up into an operative position very quickly and easily.

In use the base 10 is placed upon or held in proximity to the object with which the 40 magnifier is to enlarge, while the supporting brackets 12 are moved until the lens is the desired distance from the object, after which it may be tilted, if it is necessary, to obtain the desired angular adjustment with 45 the object to be enlarged or magnified. By having the base supporting brackets and lens frame hingedly associated it is possible to obtain any adjustment required, so that anyone may focus the reader for his own 50 particular use. After the adjustment has been made the parts may be locked in the desired position and used indefinitely, after which they may be loosened and collapsed to facilitate carrying thereof.

55 It is to be understood that the form of the invention herewith shown and described is to be taken as the preferred embodiment of the same and that various changes in the

shape, size and arrangement of parts may be resorted to without departing from the 60 spirit of the invention or the scope of the subjoined claims.

In Figures 5 and 6 the magnifier is shown as being provided with a handle which is adapted to be slid into and out of an operative position. The handle 33 is received through the members 34 and has stops 35 formed thereon to prevent separation of the base 31 and the handle 33. It will be seen that when this slideable handle with the case 70 is in use the handle is pulled out and grasped so as to facilitate movement of the magnifier over or upon the object magnified. When not in use, the handle 33 is slid along the frame so as to enable the magnifier to 75 be slipped in the case 32 until it is desired to use the same again.

Having thus described my invention, I claim:

1. In a device of the character described, 80 an open frame, a second frame within the first frame, having a contour parallel to the first frame, a hinge connection between the frames and a lens hinged to the inner frame adapted to lie therewithin when folded on 85 its pivot.

2. In a device of the character described, 90 an open frame, a second frame within the first frame, having a contour parallel to the first frame, a pair of hinges diametrically arranged uniting the two frames, and a lens within the second frame pivoted thereto, adapted to lie within the second frame when folded on its pivot.

3. In a device of the character described, 95 an open frame, a second frame within the first frame, having a contour parallel to the first frame, a hinge between the frames, a third frame hinged to the second frame and adapted to lie therewithin, and a lens in the 100 third frame.

4. In a device of the character described, 105 an open frame, a second frame within the first frame having a contour parallel to the first frame, a hinge between the frames, a lens within the second frame and hinged thereto, and a handle secured in the first frame.

5. In a device of the character described, 110 an open frame, a second frame within the first frame, having a contour parallel to the first frame, a hinge between the frames, a lens within the second frame and hinged thereto, and a handle slidingly secured to the first frame.

DENIS HENRY O'MEARA.
